TUBE CRACKING FURNACE

John B. Orr, Jr., Great Barrington, Mass.

Continuation of application Serial No. 456,437,
August 27, 1942. This application July 29, 1949,
Serial No. 107,649

19 Claims. (Cl. 23—277)

1

This is a continuation of my application Serial No. 456,437 of August 27, 1942, now abandoned, in favor of the present application.

This invention pertains to still or large multiple tube cracking apparatus, and more particularly, to an improved combination of cracking tubes in a furnace construction.

In another aspect, my invention pertains to apparatus for producing hydrocarbons, particularly, gaseous unsaturated hydrocarbons where relatively high temperatures are required.

Although the apparatus of the present invention has been designed particularly and is to be preferably used for the production of unsaturated gaseous hydrocarbons from saturated gaseous hydrocarbons employing an endothermic process, it will be apparent to those skilled in the art that other suitable uses may be made of the same and of the novel principles involved therein.

Large quantities of natural gas are available in the various oil fields of this country. But heretofore, no one has been able to provide what may be termed a practical procedure for utilizing such natural gas in the production of more desirable gases, and especially those of an unsaturated nature such as acetylene and the ethylene series. The problem of providing a suitable cracking tube arrangement that will withstand the temperatures involved is a very important one and particularly if the process is to be carried out on a commercial basis, namely, substantially continuously. Another important factor rests upon the necessity of what may be termed economic production of desired gaseous products from a given quantity of natural gas.

In view of the above and other considerations, it has been an object of my invention to provide new and improved procedure for producing unsaturated hydrocarbons, and particularly, unsaturated gaseous hydrocarbons, by endothermic treatment of saturated hydrocarbons.

Another object has been to devise a multiple apparatus arrangement for, in a practical manner, producing suitable desired gaseous hydrocarbons by thermal treatment thereof.

A further object of my invention has been to provide a new and improved form of cracking furnace or still suitable for utilizing large quantities of natural gas to produce correspondingly large quantities of desired gases.

These and many other objects of my invention will appear to those skilled in the art from the description, the drawings, and the claims, as well as from the prior art background.

2

In the drawings:

Figure 1 is a vertical-longitudinal section in elevation through an apparatus constructed in accordance with my invention and taken along the line I—I of Figure 2;

Figure 2 is an end view in elevation taken from the right of the embodiment of Figure 1;

Figure 3 is a horizontal section taken along the line III—III of Figure 2; and

Figure 4 is an enlarged sectional detail showing a cooling arrangement for outlet tubes that may be utilized in connection with the apparatus shown in Figures 1—3, inclusive.

Figure 5 is a vertical section in elevation through a single tube cracking assembly embodying my invention;

Figure 6 is a similar view of a modified arrangement employing a multi-tube assembly.

By reference to Figure 2 of the drawings, it will be noted that I have grouped a series or set of cracking tubes designated 15 about an outlet tube designed 16 in such a manner as to provide a substantial equidistant flow of the gases being exhausted from the apparatus. Such gases may consist of combustible gases, steam, inert gases, cracked gases, etc.

Steam and air used for combustion purposes may be preliminarily preheated before being introduced into the apparatus. But as shown in Figure 1, upon entry through inlet 10, they are, in any event, preheated by movement about combustion chamber portions of the cracking tubes before they enter a mixing chamber 17 within which they are combined with combustible gases, and thus, before the mixture is introduced into the cracking tubes 15.

The gases to be cracked are preferably introduced at an opposite end of the cracking tubes in such a manner that they are preferably preliminarily heated by gases in the cracking chamber before they come into direct contact with the hottest zone of the cracking chambers. In other words, the gases to be cracked are preferably introduced by some suitable means such as pipe 14 that extends along and substantially concentrically of the particular cracking chamber involved up to the hotter portions and downstream of checker brick 12, in such a manner that the gases to be cracked come into direct thermal or heat-exchange admixture with the hot burnt gases.

Referring particularly to the drawings, a represents the combustible gas to be burnt for heating purposes; B represents air or air and steam to be mixed with the combustible gas and to be

utilized in the process of combustion. As touched upon above, the air and steam are preferably preheated to a suitable temperature such as 1100° C. before being introduced through inlet 10 along passageways about each of the cracking tubes 15; the purpose is to lighten the heat exchange load of the outer portions of the tubes 15. B' represents the same air and gas after it has been further heated to substantially 1200° C. by movement about combustion chamber portions of the cracking tubes. E represents the burnt gases and steam, C represents entering gas or hydrocarbons to be cracked, such as natural gas, and D represents the exhausting gaseous mixture of cracked gases, burnt gases, steam, etc.

Combustible gases after being introduced through inlet tubes 11 mix with the heated air and steam B' in a mixing chamber 17 and then enter each of the plurality of cracking tubes 15, passing through checkerbrick portions 12 and being burnt within the combustion chambers (to the left of portions 12 in Figure 1). The mixing chamber 17 comprises a metal-enclosed insulated steam box or wall portion 18b fastened in an airtight manner against front brickwork portion 18a. An exhaust chamber 17' of similar construction is defined by wall portion 18d that is fastened in an airtight manner against the back brickwork portion 18c. As will be noted, the three brickwork portions 18a, 18, and 18c are positioned in a spaced-apart relationship in such a manner as to, in effect, provide two circulating chambers for movement of gases about the cracking tubes 15. This provides a maximum efficiency of utilization of the various materials involved, as well as a maximum life of the tubes and a retention of a suitable temperature of endothermic treatment without injury to the cracking tubes, all irrespective of the fact that these tubes are mounted in a rather closely adjacent relationship within the apparatus.

Referring to Figure 1 of the drawings, it is seen that the metal-enclosed box or enclosure 18b extends about the wall or brickwork portion 18a to provide a fluid connection or passageway for the portion of the combustion fluid, see the arrows B, which enters through the supplemental combustion fluid inlet 10 in a bottom enclosing portion 18e and flows around exterior portions of (laterally with respect to the axes of) the reaction tubes 15 into the front chamber, see the arrows B'. This supplemental fluid mixes with another portion of the combustion fluid that is introduced through the combustion fluid inlets or tubes 11.

It will be also noted that the combustion fluid inlet tubes 11 extend through and are positioned or supported by the enclosure 18b. The tubes 11 are of smaller diameter than the reaction tubes 15, have ends that are open to the front chamber, and that are in a substantially spaced-apart axial-alignment with the combustion fluid inlet opening at the front end of each associated reaction tube 15. The intermediate wall portion 18 provides a pair of chambers about exterior wall portions of the reaction tubes with the spaced-apart wall portions 18a and 18c. As indicated above, a portion of the combustion gases, such as air and steam, enter through the bottom combustion fluid inlet 10 into the chamber formed between the spaced walls 18a and 18 and move upwardly over and about the exterior walls of the reaction tubes to take up heat from the tubes before they enter the frontal, or combustion fluid mixing chamber; it is thus apparent that the

chamber between walls 18a and 18 may be termed a heat exchange chamber.

As shown particularly in Figure 4, the outlet tubes 16 are preferably water-jacketed. This helps in at least preliminarily and quickly cooling the gaseous exhaust mixture and preventing polymerization and other undesired side reactions. In this figure, 21a indicates a water inlet pipe and 21b indicates a water outlet pipe of any suitable circulatory system. As shown in this figure, the exhaust fluid outlet tubes 16 are preferably of the same length, see Figure 4 of the drawings, and also page 4, lines 13 to 17 of my application Serial No. 456,434, now abandoned, and have spaced-apart or jacketed wall portions 16 which define a cooling chamber.

Referring particularly to Figure 5, the gases are cracked in a suitable longitudinally-extending tube 20 having tube wall portions surmounted by refractory wall portions 26, 26a and 26b. Air and steam for effecting combustion may be introduced through inlet 11a and combustion gas through inlet 11 into an inlet mixing chamber 23. Such gases after being introduced in a suitable relationship enter a combustion chamber portion 24 where they are fired and heat checkerwork portions 12 at what may be termed the forward or inlet end of the refractory tube 20. Gaseous feed hydrocarbons such as natural gas that are to be cracked are introduced through inlet pipe 28 at the discharge end of the tube 20. It will be noted that this inlet pipe extends through a rear chamber 29 and a substantial distance into and in a substantially axially aligned relationship along or substantially concentrically of the outlet end of the refractory tube 20.

In accordance with my invention, the gaseous hydrocarbons from pipe 28 mix somewhat turbulently with combustion gases in the form of a superheated fluid in the portion 27 in such a manner that the heat of the combustion gases cracks or endothermically converts the gaseous hydrocarbons into desired unsaturated hydrocarbon such as acetylene or ethylene or those of the ethylene series. The hot cracked gases leave the refractory tube through the outlet chest or chamber 29 and pipe 30 conducts them to a suitable water condenser and stripping plant installation. It will be apparent that the gases to be cracked or heated, at least initially, flow or move counter to the heating fluid, mix with such fluid, and then flow toward the chest 29. In this manner, a maximum thermal heat exchange relationship is provided in that the gases to be cracked are preliminarily heated before they are subjected to maximum heat and direct admixture in the chamber portion 27. The tube 28 also aids in quickly cooling the cracked gases and preventing undesired side reactions as well as polymerization of the acetylene. The inlet and outlet chest or chamber portions 23 and 29 aid in increasing the thermal efficiency of the cracking or reaction tube 10. An effective admixture of the gases is accomplished by reason of turbulence existing at the inner end of the supply tube 28. The arrangement also provides for a maximum control of treatment to effect optimum results.

In the drawing of Figure 6, I have endeavored to avoid unnecessary repetition by referring to parts that are substantially similar to those specified in the description of Figure 5 by the same numerals.

In Figure 6, gas is introduced by pipe 22 through a plurality of branches a, b, and c, into inlet chest

or preliminary chamber portion 23 that serves as a common combustion fluid mixture supply for each of a series of refractory cracking tubes 20. It will be noted that each of the pipe inlet portions *a*, *b*, and *c* is positioned in a substantially axially aligned relation with a corresponding reaction tube 20. Air and steam used for combustion purposes is introduced through inlet pipe 31 at the top end of a transverse passageway in such a manner as to flow over and about the hotter portions of each of the cracking tubes 20 in succession as indicated by the arrows, and through space or chest portions 32*a*, 32*b*, 32*c*, and 32*d* (providing the transverse passageway), through a passageway connection 33 in the refractory block portion 26 (adjacent the bottom end of the transverse passageway), and into the fuel mixing chamber 23 where the air is mixed with the fuel to provide a suitable combustible mixture.

The gases to be cracked are introduced through each of the tubes 20 in a manner similar to that described in connection with Figure 5. All of the refractory tubes 20 discharge into a common discharge chest or chamber 29 which is provided with an outlet pipe 30 having substantially V or U-shaped branch portions substantially symmetrically located along the chest 29 and with respect to the discharge portions of the refractory tubes.

In accordance with this multi-tube assembly, the air and steam are preliminarily heated by circulating around the combustion furnace tubes, which also controls the temperature of the tubes. This prevents the individual tubes of a multi-tube assembly from reaching a temperature of over approximately 1500° C., which I have found is destructive of their useful life. I have also shown fluid connections disposed in such a manner that the hot gases moving from the ends of each of the tubes 20 toward cooling apparatus reach the cooler at the same period of time. This is important in obtaining desired results.

Referring particularly to Figure 6 of the drawings, it will be noted that separated or spaced-apart walls 26 and 26*c* traverse the reaction tubes 20 and support and position them in a spaced-apart relationship in respect to each other. It will also be noted that walls 26*a* and 26*b* extend from the second-mentioned of the separated walls 26*c* to the rear ends of the reaction tubes 20.

As will be apparent to those skilled in the art, one of the outstanding features of the apparatus of this invention is the fact that the wall temperatures of the cracking tubes, and particularly portions thereof that are subjected to the hottest temperatures such as the combustion chamber portions, can be controlled as to temperature to provide optimum results. In addition, the gas to be cracked is introduced into the cracking chambers in such a manner that the cold point of weakness in the construction has been eliminated; that is, heretofore the cracking tube has been fastened into the cracking chamber and this has been eliminated. Also, as at least implied above, there is a much better mixing of both hot and cool gases with a maximum efficiency of thermal treatment being effected.

It will be apparent that the embodiment of my invention shown in Figure 1 provides a pre-heating flow chamber between walls 18*a* and 18*b* for the air and steam. It is also apparent that this chamber serves to cool the exterior walls of the reaction tubes 15. The embodiment of Figure

5 shows a closed off chamber. A comparison of Figures 1 and 3 of the drawings discloses that in both embodiments a pair of chambers or spacings are provided about the exterior wall portions of the reaction tubes 15.

As shown particularly in Figures 1 and 3, the checkerwork or refractory portions 12 extend or project inwardly of inner wall portions of the reaction tubes and are spaced adjacent to, but beyond the front ends of the combustion fluid inlet openings of the reaction tubes 15. For the purpose of better description, each reaction tube 15 may be termed as having a combustion fluid inlet opening at one end thereof open to the front chamber and as having an exhaust fluid outlet opening at the other or rear end thereof open to the rear chamber. That is, as indicated by the arrows of these figures, the combustion fluid enters the inlet ends or portions of the reaction tubes 15 and is exhausted from the outlet ends or portions thereof. The indicated refractory nature of the portions 12, which are positioned to extend within and in a spaced relation about the inside of the reaction tubes 15, see the sectioning of these figures, enables them to withstand high temperatures and to promote fluid combustion.

It will be noted that each feed fluid tube or inlet 14 extends through and is positioned or supported by the enclosing wall portion of the exhaust chamber 17, and extends through the exhaust fluid outlet opening of a corresponding reaction tube 15 for a substantial distance therealong. That is, each tube 14 which is of smaller diameter than a corresponding reaction tube 15, serves as a fluid feed tube for the reaction hydrocarbons to be thermally converted. The extending portion of the tube 14 projects into and in a spaced relation with inner walls of the corresponding or associated reaction tube 15 and is open to the inside of the reaction tube, approximately intermediate the combustion fluid inlet and the exhaust fluid outlet openings thereof at a position that is spaced from the refractory portions 12 towards the exhaust fluid outlet opening of the reaction tube, or in other words, is open to the inside of the reaction tube between the checkerwork portions 12 and the exhaust fluid outlet opening of the reaction tube.

In the embodiments of Figures 5 and 6, I have shown a different species of apparatus. For example, in Figure 6, the air and steam are introduced from the top of the heat exchange chamber rather than from the bottom as indicated in the embodiment of Figure 1, and the connection between the vertical passageway formed by the separated refractory walls is at the bottom through the front wall and not about the top of the front wall as in the later figure.

In the embodiment of Figure 3, an enclosing portion 18*b* extends about the wall portion 18*a* and is connected to an enclosing portion 19*b* (for wall portions 18 and 18*c*) to define a front mixing chamber 17 and a heat exchange chamber (see arrows B) between the wall portions 18*a* and 18*b*.

As will be appreciated and as intimated before, the present invention is not limited to the exact apparatus shown or to the exact utilization thereof in that many substitutions, additions, subtractions, and modifications thereof may be made without departing from the invention spirit and scope thereof.

What I claim is:

1. A furnace for thermally converting normally gaseous hydrocarbons into other hydrocarbons comprising a plurality of horizontally extending reaction tubes supported by and positioned in separated refractory walls, a first wall of said separated supporting walls at one end of said tubes and a second of said walls together with said first wall defining a vertical passageway about the exterior portions of said tubes, a front enclosing wall for said furnace separated from said first supporting wall and extending so as to form a relatively narrow frontal chamber into which said tubes open and which communicates at the top thereof with said vertical passageway, a third wall of said supporting walls at the opposite ends of said tubes and a rear enclosing wall for the furnace defining a relatively narrow rear chamber into which said tubes open, a plurality of inlets into said first chamber, an inlet into the bottom of said vertical passageway, a plurality of small outlets from said rear chamber, and pipes extending through said rear chamber and for a substantial distance into said tubes and concentrically arranged therein.

2. A furnace for thermally converting normally fluid hydrocarbons into other hydrocarbons comprising a plurality of reaction tubes extending in substantially the same direction supported by and positioned in separated refractory walls, a first wall of said separated supporting walls adjacent one end of said tubes, a second of said walls together with said first wall defining a passageway extending in another direction about the exterior portions of said tubes, a front enclosing wall for said furnace separated from said first supporting wall and extending so as to form a frontal chamber into which said tubes open and which communicates adjacent one end thereof with said passageway, a third wall of said supporting walls at the opposite ends of said tubes, a rear enclosing wall for the furnace defining a rear chamber into which said tubes open, a plurality of inlets into said first chamber, an inlet into said passageway adjacent another end thereof, a plurality of outlets from said rear chamber, and tubes of smaller diameter than said reaction tubes extending through said rear chamber and for a substantial distance into said tubes and concentrically arranged therein.

3. A furnace as defined in claim 2 wherein each of said plurality of inlets is a tube positioned to extend into said first chamber in substantial axial alignment with a corresponding reaction tube of said plurality of reaction tubes.

4. Thermal furnace apparatus suitable for continuously converting fluid hydrocarbons into other hydrocarbons comprising, a plurality of reaction tubes, spaced-apart supporting wall portions within which said reaction tubes are positioned, one of said wall portions being located adjacent one end of each of said reaction tubes, a second of said wall portions being located adjacent the other end of each of said reaction tubes, a third of said wall portions being located intermediate said first and second-mentioned wall portions and defining a heat exchange chamber with said first-mentioned wall portion, said third-mentioned wall portion defining a second chamber about exterior portions of said tubes with said second-mentioned wall portions, enclosing portions across said second and third-mentioned supporting wall portions, enclosing portions across said first and third-mentioned

supporting wall portions, a portion of said last-mentioned enclosing portions extending in a spaced relationship about one end of and along said first-mentioned supporting wall portion and defining a third chamber in front of said first-mentioned supporting wall portion into which one end of each of said reaction tubes open and also defining a fluid passageway between one end of said heat exchange chamber and said third chamber, a combustion fluid inlet open to an opposite end of said heat exchange chamber, an enclosing portion in a spaced relationship along said second-mentioned supporting wall portion and defining a fourth chamber in back of said second-mentioned supporting wall portion into which the other ends of said reaction tubes open, a plurality of combustion fluid inlets open to said third chamber, a plurality of exhaust fluid outlets open from said fourth chamber, and feed fluid tubes extending through said fourth chamber and for a substantial distance within said reaction tubes.

5. Furnace apparatus suitable for continuously thermally converting fluid hydrocarbons comprising, a plurality of spaced-apart reaction tubes, each of said reaction tubes having a combustion fluid inlet opening at a front end thereof and an exhaust fluid outlet opening at a rear end thereof, an enclosure for said reaction tubes having a pair of supporting wall portions spaced along said reaction tubes and defining a heat exchange chamber about exterior walls of said reaction tubes, a front enclosure extending about and in a spaced relationship with front ends of said reaction tubes and defining a front chamber into which the combustion fluid inlet opening of each of said reaction tubes open, a rear enclosure extending about and in a spaced relationship with the rear ends of said reaction tubes and defining a rear chamber into which the exhaust fluid outlet openings of each of said reaction tubes open, a plurality of combustion fluid inlet tubes extending through said front enclosure and open to said front chamber in a spaced-apart and substantially axially-aligned relationship with the combustion fluid inlet openings of each of said reaction tubes, a plurality of feed fluid tubes extending through said rear enclosure into said rear chamber and through the exhaust fluid outlet openings of and for a substantial distance substantially concentrically along said reaction tubes, and a plurality of substantially equal length exhaust fluid outlet tubes extending through said rear enclosure and open to said rear chamber.

6. Furnace apparatus as defined in claim 5 wherein, a cooling fluid inlet and outlet are connected to opposite end portions of said heat exchange chamber.

7. Thermal apparatus suitable for continuously converting fluid hydrocarbons comprising, a reaction tube, said reaction tube having a combustion fluid inlet opening at one end thereof and an exhaust fluid outlet opening at the other end thereof, an enclosure having spaced-apart walls supporting said reaction tube and defining a heat exchange chamber about exterior walls of said reaction tube, an enclosure having a portion spaced from and extending about the combustion fluid inlet opening of said reaction tube and defining a front chamber about said reaction tube into which the combustion fluid inlet opening of said tube opens, a fluid connection between an end of said heat exchange chamber and said front chamber, a combustion fluid inlet

tube extending through said second-mentioned enclosure into said front chamber and being open thereto, said combustion fluid inlet tube being positioned in substantial axial alignment and in a spaced relationship with the combustion fluid inlet opening of said reaction tube, a fluid inlet connection through said first-mentioned enclosure into an opposite end of said heat exchange chamber for introducing additional combustion fluid through said heat exchange chamber and said first-mentioned fluid connection into said front chamber, and a supported feed fluid inlet tube extending through the exhaust outlet opening of said reaction tube and being open to the inside of said reaction tube approximately intermediate the combustion fluid inlet and exhaust fluid outlet openings of said reaction tube.

8. Thermal apparatus suitable for continuously converting fluid hydrocarbons comprising, a reaction tube, said reaction tube having a combustion fluid inlet opening at one end thereof and an exhaust fluid outlet opening at the other end thereof, segregated supporting walls for said reaction tube extending laterally of said reaction tube and positioned in a spaced-apart relationship along exterior walls of said tube and defining a chamber therebetween for the exterior walls of said tube, an enclosure positioned in a spaced relation about the combustion fluid inlet opening of said reaction tube and defining a chamber into which the combustion fluid inlet opening of said reaction tube opens, a combustion fluid inlet tube extending through said enclosure into said last-mentioned chamber and being open thereto, a second enclosure positioned in a spaced relation about the exhaust fluid outlet opening of said reaction tube, and a feed fluid inlet tube extending through said second-mentioned enclosure into the exhaust fluid outlet opening of and for a substantial distance concentrically along said reaction tube and open to the inside of said reaction tube at a position that is spaced from the combustion fluid opening of said reaction tube.

9. Thermal apparatus suitable for continuously thermally converting fluid hydrocarbons comprising, a reaction tube, said reaction tube having a combustion fluid inlet opening at one end thereof and an exhaust fluid outlet opening at the other end thereof, wall portions supporting said reaction tube and having an enclosing portion in a spaced relation about the combustion fluid inlet opening of said reaction tube and defining a chamber into which the combustion fluid inlet opening of said reaction tube opens, a combustion fluid inlet tube having a smaller diameter than said reaction tube and being supported by and extending through said enclosing portion into said chamber, the extending end of said combustion fluid inlet tube being open to said chamber and positioned in substantial axial alignment and in a spaced relationship with the combustion fluid inlet opening of said reaction tube, refractory means positioned beyond the combustion fluid inlet opening of and within said reaction tube, said wall portions having an enclosing portion in a spaced relation about the exhaust fluid outlet opening of said reaction tube and defining a chamber into which the exhaust fluid outlet opening of said reaction tube opens, and a feed fluid inlet extending through said last-mentioned enclosing portion and for a substantial distance along and open to the inside of said reaction tube approximately intermediate

the combustion fluid inlet opening and the exhaust fluid outlet opening of said reaction tube at a position that is spaced from said refractory means towards the exhaust fluid outlet opening of said reaction tube.

10. Furnace apparatus suitable for continuously thermally converting fluid hydrocarbons comprising, a reaction tube, said reaction tube having a combustion fluid inlet opening at one end thereof and an exhaust fluid outlet at the other end thereof, refractory portions positioned within said reaction tube adjacent to and spaced from the combustion fluid inlet opening of said reaction tube, a feed fluid tube of smaller diameter than said reaction tube having a portion extending through the exhaust fluid outlet opening of said reaction tube and along said reaction tube for a substantial distance and being open to the inside of said reaction tube at a position within said reaction tube that is between said refractory portions and the exhaust fluid outlet opening of said reaction tube, means supporting said reaction tube and said second-mentioned tube in the relationship as above defined; and an enclosure in a spaced relationship about the combustion fluid inlet opening of said reaction tube and defining a chamber into which the combustion fluid inlet opening of said reaction tube opens, and a combustion fluid inlet through said enclosure into said chamber.

11. Thermal apparatus suitable for continuously converting fluid hydrocarbons comprising, a reaction tube, said reaction tube having a combustion fluid inlet opening at one end thereof and an exhaust fluid outlet opening at the other end thereof, supporting wall portions for said reaction tube and having an enclosing portion extending in a spaced relation about the combustion fluid inlet opening of said reaction tube and defining a chamber into which said reaction tube opens, a combustion fluid inlet tube having a portion extending inwardly through said enclosing portion into said chamber and being open to said chamber, the inwardly extending open portion of said fluid inlet tube being positioned in substantial axial alignment and in a spaced relationship with the combustion fluid inlet opening of said reaction tube, a feed fluid inlet through said reaction tube and being open to the inside of said reaction tube at a substantial distance from the exhaust fluid opening and approximately intermediate the combustion fluid inlet and exhaust fluid outlet openings of said reaction tube, and positioning means for said feed fluid inlet.

12. A thermal apparatus suitable for continuously converting hydrocarbons comprising a reaction tube, said reaction tube having a combustion fluid inlet opening at one end thereof and an exhaust fluid outlet opening at the other end thereof, refractory means positioned within said reaction tube adjacent to and spaced from the inlet opening thereof, an enclosure about said combustion fluid inlet opening of said reaction tube and defining a mixing chamber into which the combustion fluid inlet opening of said reaction tube opens, a pair of combustion fluid inlets open into said mixing chamber, and a reaction hydrocarbon feed fluid inlet open to said reaction tube at a substantial distance from the exhaust fluid opening and approximately intermediate the combustion fluid inlet and the exhaust fluid openings thereof at a position within said reaction tube that is spaced between

11

Said refractory means and the exhaust fluid outlet opening of said reaction tube.

13. A thermal apparatus suitable for continuously converting fluid hydrocarbons comprising, a reaction tube having a combustion fluid inlet opening at one end thereof and an exhaust fluid outlet opening at the other end thereof, supporting means for said reaction tube, spaced-apart refractory portions within and about the inside of said reaction tube adjacent to and spaced from the inlet opening of said reaction tube, a feed fluid inlet tube positioned to extend through and a substantial distance from the exhaust fluid opening of and substantially concentrically along said reaction tube, said feed fluid inlet tube being open to said reaction tube at a substantial distance from the exhaust fluid opening and approximately intermediate the combustion fluid inlet and exhaust fluid openings thereof at a position within said reaction tube that is spaced from said refractory portions and towards the exhaust fluid outlet opening of said reaction tube, and positioning means for said feed fluid inlet tube.

14. Thermal apparatus suitable for continuously converting fluid hydrocarbons comprising, a reaction tube, said reaction tube having a combustion fluid inlet opening at one end thereof and an exhaust fluid outlet opening at the other end thereof, refractory means positioned within said reaction tube adjacent to and spaced from the inlet opening thereof, a reaction hydrocarbon feed fluid inlet extending through and along said reaction tube and being open to the inside of said reaction tube at a substantial distance from the exhaust fluid opening and approximately intermediate the combustion fluid inlet and exhaust fluid openings of said reaction tube at a spaced location from said refractory means and between said refractory means and the outlet opening of said reaction tube, and positioning means for said feed fluid inlet.

15. Thermal apparatus suitable for continuously converting fluid hydrocarbons comprising, a reaction tube, said reaction tube having a combustion fluid inlet opening at one end thereof and an exhaust fluid outlet opening at the other end thereof, refractory means positioned within said reaction tube adjacent to and spaced from the inlet opening thereof, a feed fluid inlet open to said reaction tube at a substantial distance from the exhaust fluid opening and approximately intermediate the combustion fluid inlet and exhaust fluid openings of said reaction tube at a spaced location from said refractory means and between said refractory means and the outlet opening of said reaction tube, positioning means for said feed fluid inlet, a wall positioned about the exhaust fluid outlet of said reaction tube so as to define a chamber into which said reaction tube opens, and a fluid-jacketed exhaust fluid cooling tube open to the chamber and extending through said wall.

16. Furnace apparatus suitable for continuously thermally converting fluid hydrocarbons into other hydrocarbons comprising, a reaction tube, said reaction tube having a combustion fluid inlet opening at one end thereof and an exhaust fluid outlet opening at the other end thereof, refractory portions positioned to project within inner walls of said reaction tube adjacent to and spaced from the inlet opening thereof, supporting means for said reaction tube, a feed fluid inlet tube of smaller diameter than said reaction tube and

12

having a portion extending for a substantial distance into and along said reaction tube through and from the exhaust fluid outlet opening of said reaction tube, said extending portion of said feed inlet tube being open to the inside of said reaction tube at a position within said reaction tube that is spaced from said refractory portions and towards the exhaust fluid outlet opening of said reaction tube, and means positioning said extending portion of said feed fluid inlet tube within said reaction tube in a spaced relationship therewith respect to the inner walls of said reaction tube.

17. A furnace for converting normally gaseous hydrocarbons into other hydrocarbons comprising a plurality of horizontally extending reaction tubes supported by and positioned in separated refractory walls, a first wall of said separated supporting walls at one end of said tubes and a second of said walls together with said first wall defining a vertical passageway about the exterior portions of said tubes, a front enclosing wall for the furnace separated from said first supporting wall and extending so as to form a relatively narrow frontal chamber into which said tubes open and which communicates adjacent a bottom end thereof and through said first supporting wall with said vertical passageway, an inlet into the top end of said vertical passageway, a third wall of said supporting walls at the opposite ends of said tubes, a rear enclosing wall for the furnace defining a relatively narrow rear chamber into which said tubes open, a plurality of inlets into said first chamber, a plurality of outlets from said rear chamber, and pipes extending through said rear chamber and for a substantial distance into said tubes and concentrically arranged therein.

18. A furnace as defined in claim 17, wherein said outlets have substantially V-shaped branch portions extending from said rear chamber, said branch portions being connected to a common outlet portion.

19. A furnace as defined in claim 17, wherein each of said inlets into said first chamber is a pipe portion positioned in a substantially axially aligned relationship with the front end of a corresponding one of said reaction tubes, and said reaction tubes are positioned in a spaced-apart relationship with respect to each other by said separated refractory walls.
